PAUL JUNAS, JR., OF LANSFORD, PENNSYLVANIA

HAIRCLOTH

Application filed June 20, 1929. Serial No. 372,450.

This invention relates to what is generally known in the trade as a hair cloth, that is, an apron like protective covering which is placed over the clothing of a patron while cutting the hair in a barber parlor or the like. At the present time there is an unusual trend of feeling toward promoting sanitation and convenience of customers. As a general rule the hair cloth now employed is 10 of percale, calico and analogous light weight flimsy material. It is necessary to launder this from time to time and to starch it in order that it will maintain neatness of appearance and rigidity. Starch is depended 15 upon in most instances to permit the cloth to shed the cut hair.

It is now a matter of common knowledge that hair cloths of this type do not properly shed the hair. It sticks to the material and 20 is a nuisance to the customer. In fact it is unusually unpleasant in warm weather when the hair, which clings thereto, readily adheres to the moist skin. As a rule a shake does not clean and freshen the apron. 25 I have evolved and produced a simple and inexpensive hair cloth which is accomplished by a multiplicity of advantages. First it is made of an especial texture of material which renders it substantially hair proof; secondly, 30 it is practically water proof, and has the additional function of serving as a shampoo cloth; third, it is substantially ash proof and not likely to burn from dropping sparks while the customer smokes; fourth, it is not 35 easily soiled and is very easily cleaned.

In the drawings:

Figure 1 represents a side elevational view showing the cloth in use, the same being of general or ordinary configuration and applied in substantially the well known manner.

Figure 2 is a fragmentary plan view showing the yoke construction and the multiple adjusting fastening means.

The gist of the invention is in the provision of a barber's apron or hair cloth as it is generally called, which is made of a rubberized glossy finished cloth of a thickness to render it substantially hair proof, washable, and otherwise sanitary. In the experiments made in selection of the material I have found it expedient to employ a rubberized gingham which is of an ornate variety and color to avoid soiled appearance. The material found to be satisfactory for the purpose is known on the market as Staso. This 55 is a material which is susceptible of being washed off with soap and water, and the finish is sufficiently glossy to cause the clipped hair to slide off immediately.

The rubberized cloth apron or hair cloth 60 is generally designated by the reference character 3 and is of general or ordinary configuration in outline. It is made with the reinforced neck yoke cut out as at 4. On one side I provide a multiplicity of fastening 65 studs 5 for adjustable cooperation with the primary snap fastener 6. This allows the yoke to be wrapped around the neck and the snap to be adjusted to render the yoke adjustable to necks of different sizes. 70

It is understood that the primary factor of the invention is the texture of the material from which the hair cloth is made, rendering it susceptible of inexpensive manufacture, comfortable use, to promote sanitation and to fulfill the requirements enumerated at the outset of the description. 75

It is thought however that persons skilled in the art to which the invention relates will be able to obtain a clear understanding of 80 the same after considering the description in connection with the drawings. Therefore, a more lengthy description is believed to be unnecessary.

Minor changes in shape, size, and materials may be resorted to within the spirit and scope of the invention as claimed.

Having thus described the invention, what I claim as new and desire to secure by Letters Patent, is:

As a new article of manufacture, a barber's accessory comprising a combined hair cloth and shampoo apron composed of a single length of rubberized cloth having a gloss finish to render it susceptible of readily shedding the clipped hair, said cover having a cut-out neck yoke portion, cut inwardly from one end thereof defining a neck accommodating opening, a plurality of fastener members secured to the cloth adjacent one edge 95 100 of the opening, and a single fastener element secured to the cloth adjacent an opposite edge of the opening and adapted to engage selectively the first mentioned fastener members.

5 In testimony whereof I affix my signature.
